WRAP STRIPE KNITTING MACHINE AND
METHOD

Robert H. Lawson, Pawtucket, and Isaac H. C. Green, Central Falls, R. I., assignors to Hemphill Company, Central Falls, R. I., a corporation of Massachusetts

Application July 21, 1936, Serial No. 91,744

14 Claims. (Cl. 66—135)

This case involves an invention in mechanism for knitting wrap patterns on circular, independent needle knitting machines. The invention is applied to wrap machines of similar type to that shown in Hemphill Patent 1,702,608, and is a continuation in certain respects of co-pending applications Ser. Nos. 689,449, Patent No. 2,104,232 and 699,714, Patent No. 2,111,492.

In the drawings:

Fig. 1 is a section of the simplest form of the device showing the manner in which yarn wrapping fingers are controlled;

Fig. 2 is an elevation of the wrapping head showing the cams;

Fig. 3 is a view of the head as seen from below, Fig. 1;

Fig. 4 is a sectional view similar to Fig. 1 but taken through a different plane for the purpose of showing yarn wrapping fingers in another position;

Fig. 5 is a development of the finger controlling cams;

Fig. 6 is a section showing a fragment of the head and the cam for holding fingers in outer position;

Fig. 7 is a detail of a cam or plate removable for the purpose of changing yarn guiding fingers;

Fig. 8 is a diagrammatic view showing needle selection as applied to this form of the invention;

Fig. 9 is a plan of certain parts of the machine, a group of needles and a group of fingers illustrating the action of the wrapping point;

Figs. 10 and 11 are detail views of one of the yarn wrapping fingers;

Fig. 12 is an elevation showing the general construction of a modified form of the device;

Fig. 13 is a sectional view of the same;

Fig. 14 is a view of the wrapping head as seen from below;

Fig. 15 is a sectional view taken on a different plane from that upon which the section of Fig. 13 is taken;

Fig. 16 is a development of the cam assemblies;

Fig. 17 is a detail similar to that of Fig. 7, of a cam or plate removable for purpose of changing yarn guiding fingers;

Fig. 18 is a section showing part of the yarn finger carrier and one of the cams functioning therewith;

Fig. 19 is a section of a second modification of the invention;

Fig. 20 is a section corresponding to Fig. 19 but taken on a different plane;

Fig. 21 is a development of part of the cam assembly;

Fig. 22 is a section showing some of the cams for rocking yarn fingers; and

Fig. 23 is a diagrammatic view showing the 5 needle selection employed with this second modification of the invention.

Fig. 24 is a fragmentary view showing the lever and connections for raising the wrap mechanism and for retaining the fixed portions thereof in 10 proper relative position.

The mechanism for wrapping pattern threads which forms the subject matter of this case is similar to that shown in Hemphill Patent 1,702,608 in that an eccentrically mounted wrapping head is employed which is arranged to feed a plurality of wrap threads to selected needles. The eccentrically mounted head is rotated at the same angular speed as the needle cylinder carrying needles which are to be wrapped and for 20 a general understanding of such wrapping, reference is made to the patent above mentioned. One of the objects of this invention is to provide means for wrapping a great number of separate wrap yarns whereby it will be possible to ornament a fabric with a very large number of colors. This also makes it possible to wrap different colors upon needles which are adjacent or very closely adjacent, these adjacent needles being wrapped with different threads in the same 30 course of knitting. It is a further object of the invention to wrap patterns wherein one color appears within another color, this being extremely desirable especially in ornamenting certain types of hosiery.

Another object of the invention is to provide a simple and compact wrapping device which will not interfere with other functions of the machine, and which will be found to produce its pattern throughout the fabric without any deviation from the original pattern contemplated. In accordance with the practice on Banner wrap machines, this wrapping device is to be operated in conjunction with sinker reverse plating or other forms of pattern devices if desired. Other 40 objects of the invention will appear as the disclosure progresses.

These desirable objectives are accomplished by the combined movement of needles as they are selected and of wrapping fingers as they are 50 moved downwardly at about the same time and then inwardly of the needle circle after wrapping a group of selected needles. The double movement of wrapping fingers is essential in the eccentrically mounted wrapping device as em- 55

- ployed in Banner machines to allow wrapping with a great many different colors and at the same time, to retain all the advantages of the eccentrically mounted wrapping device, that is,
5. wrapping over an extended panel of needles and in a positive, simple way. The selection of needles is accomplished by any suitable means, one particular scheme being illustrated in this case, but not representing the only means available;
- 10 it should function to raise needles to wrapping position as rapidly as possible. The fingers are simultaneously moved down by a cam which is reasonably steep and this combined movement brings a finger and its wrap yarn into effective
- 15 engagement with a group of needles to be wrapped in the shortest possible time thus preventing wrapping of needles not to be included in the group selected also allowing wrapping fingers to be spaced very closely adjacent without
- 20 interference of the neighboring wrap yarns.
- The inward movement of each wrap yarn guiding finger terminates the effective wrapping by that finger in a much shorter time than could be accomplished with the eccentric wrapping
- 25 device of the previous type employed on Banner machines as exemplified in Patent Number 1,702,608. This terminating of the wrapping movement by swinging a finger inwardly across the needle circle assures that that finger will
- 30 wrap a maximum number of needles in a group without interference with the next adjacent finger and without accidentally wrapping any needles in another group. It is briefly the effect of these additional movements as imparted to the
- 35 wrapping fingers in conjunction with the selective movement imparted to needles which makes it possible to employ a great number of colors or individual wrapping threads on a small, eccentrically mounted wrapping mechanism of the
- 40 Banner type. None of the usual advantages of said wrapping mechanism have to be sacrificed to obtain the additional number of wrapping yarns, nor is it necessary to sacrifice any of the accuracy with which selected needles will be
- 45 wrapped with the proper thread.

Now referring to the figures, the wrapping head includes and is fixed to the lower end of a spindle 1. To this spindle has been fixedly attached a hub or wrap yarn guiding finger carrier 2, in this particular instance the two are fixed together by means of a screw 3 which serves as a key. The hub or guide carrier 2 has a plurality of tricks or slots cut lengthwise thereof within which the guides are freely slideable. Any desired number of slots may be cut within the carrier up to a number equivalent to the number of needles employed in the machine and which might be wrapped by guiding fingers inserted in the slots, however, it would ordinarily be satisfactory to employ about half as many guides as needles, and for many purposes much less than that number will suffice. One convenient and a preferred construction is that of a carrier with one-half as many slots as the machine with which it is to be used has needles, and employing one guide in every third slot. The additional slots provide for spacing and grouping the guides for special purposes. Such a wrap machine would have about forty fingers in service and thus might be employed to feed forty different colors, although the invention is well adapted to feed many more wrap threads and incidentally many more colors.

The wrap fingers are illustrated at 4 and have butts 5 about midway of their length and are

provided at their lower ends with an opening 6 through which a yarn is to be threaded. Several of these yarns will be brought down from a supply creel rotating on the same spindle but at a higher elevation, to pass through one of a series of openings 7 cut within the carrier 2. A cam structure is maintained in fixed position and is disposed about the carrier and serves the purpose of moving the wrap fingers vertically within their slots, rocking them within the slots for a purpose to be described and further, maintain the fingers within the carrier and in proper working position with respect to the circle of needles, selected ones of which are to be wrapped. This cam structure includes a cap 8, a sleeve 9, cut away at one side as illustrated in Fig. 2, and a lower cam ring 10. The sleeve 9 and cam ring 10 are constructed in such a manner that they provide a pathway 11 within which the butts 5 are guided. This pathway serves to impose vertical movements to the fingers.

The cam ring 10 is attached and maintained in permanent relationship to the sleeve 9 by means of the connecting pieces 12 and 13. The opening between the two as indicated at 11 is sufficient to allow easy passage of the butts 5 and maintains the butts and incidentally the fingers at their higher level except when they pass down the inclined part of the pathway 14, along the lower horizontal part 15 prior to being elevated by the inclined edge 16 of ring 10, Fig. 5. For the purpose of simplifying the removal of fingers, the ring has been slotted at one side thereof and a plate 17 having a filler piece 18 is attached by means of screws so that the filler 3 piece completely closes the slot and presents a continuous and smooth surface to the butts 5 and the fingers 4. By turning the carrier until that particular finger which it is desired to take from the same comes opposite the slot or opening, any finger may be removed at the opening left as this plate is removed.

All of this cam structure is attached by means of suitable screws 19 (three such screws being shown herein) taking within slots 20 in the cap 8. This cap has a part 21 which overlies a flange 22 projecting from the upper end of the carrier and which also bears within an annular bearing cut within sleeve 9, a complete groove thus being formed within which the flange 22 has a working fit. Obviously the slots or tricks cut in the carrier are also cut in the flange. This flange 22 allows the cam assembly to be held stationary while the carrier and wrap yarn guiding fingers rotate within it, the said flange serving to maintain the proper axial relationship between the cam assembly and the carrier itself. The ring 8 is provided with a slot 23 within which a pin may engage for preventing rotation of the cam assembly and also for lifting the entire wrapping mechanism at such times as it is to be moved away from the needles as for knitting the heel or toe and when transferring. The mechanism for raising the wrap head is similar to that shown in Lawson et al. 1,702,608, Lawson 6,2104,232 and also to that of most Banner wrap machines. Here a lever 99 has a pin or projection 98 which engages within a proper opening such as at 23, Fig. 1, and as the lever is raised or lowered the position of the wrap mechanism 70 will be altered accordingly. Incidentally, the fixed cam elements are prevented from rotating by this raising and lowering means so that as the wrap fingers are rotated with their carrier, their butts will be engaged and actuated by the 75

cams. The lever 99 is operated from cam means on the machine to lift the head to different positions as required at the different phases in the knitting of a stocking, this all being known and described in previous Hemphill patents such as Patent Number 1,702,608. At certain times the roller 100 is engaged by other means on the latch ring in a manner and for a purpose not necessary to be described here as the same forms no part of the present invention.

Each of the slots cut within the carrier has been cut at an angle to the vertical and deeper at the lower end as shown at 24. This deepening of the slot at the lower end provides for rocking fingers in such a manner that they cross the needle circle more quickly than they would if the eccentricity of the head alone was to be depended upon. Cams 25 and 26 attached to sleeve 9 and ring 10 respectively serve to control this rocking movement. Cam 26 is adjustably attached by means of screws 27 passing through slots in the cam and provides for rocking the fingers inwardly after they have been moved down by the inclined part of the slot 14. This cam is beveled at either end as shown in Fig. 3 and maintains the fingers rocked inwardly for about 45 degrees of carrier travel. The cam 25 is attached in a similar manner to the part of sleeve 9 which circumscribes the carrier below the opening 9'. Cam 25 prevents the fingers 4 from accidentally starting their rocking movement prior to contact with cam 26. This cam 25 has one end 28 shown in dotted lines, Fig. 3, which controls the upper ends of the fingers to prevent them from swinging out into the opening 9'. The connecting portion of the sleeve 9 which is beneath the opening 9' and indicated in Figs. 1, 5 and 6 at 29, has been beveled so that the upper ends of these fingers may swing outwardly when they are forced to do so under the action of cam 26.

At the right hand end, Fig. 5, of this beveled part of the connecting portion 29 the fingers will again be swung back into a vertical position and will be maintained in that position throughout the rest of their travel prior to being brought down for wrapping on the next course.

Now referring to Figs. 8 and 9, action of the needles incidental to selection and the operation of the fingers wrapping selected needles will be described. Needles are to be selected in any convenient manner, in this particular example needles 30 have selecting jacks 31 beneath them which are to be selected by any one of a series of cams or plungers 32 acting upon one of the removable butts 33. These plungers or cams 32 may be manually moved to and from butt engaging position, however, they will normally be controlled by a pattern drum or the like. After being selected, a jack will be engaged by cam 34 which contacts the master butt 35, the jack and its needle will be raised to a height in which the needle will be wrapped by one of the fingers 4. In the illustration of Fig. 8 two groups of needles are shown raised for wrapping, with one needle between the groups which has not been selected missing the wrap thread. After being wrapped these needles will move down to pass through the knitting cams with the remaining needles to knit and thereafter cast off their loops and the wrap thread if there be any.

In Fig. 9 several groups of needles which have been selected are indicated as being wrapped by fingers which are first shown after they have passed outwardly over the needle circle due to

the eccentricity of the wrapping mechanism, and then being shown after passing through the circle of needles to the inside thereof as they contact with cam 26. After being moved quickly within the circle of needles, the fingers are progressively swung back to their original position but at that time the carrier 2 has moved to such a position that all fingers are within the needle circle anyway. The hook 36 depending from arm 37 is of the usual construction employed in Ban- 10 ner machines and assists in the needle wrapping as shown. The binder plate is illustrated at 38 while the elements 39 and 40 serve in the usual manner to keep wrap floats out of the binder and confined to a position within the needle 15 circle wherein no interference will be encountered for these floats or other yarns.

From an inspection of Fig. 9 it can be seen that groups of needles which are very closely adjacent are to be wrapped with different threads and 20 thus different colors may be interposed upon the fabric in very close proximity to one another, also one color may be inserted between other colors without difficulty. Due to the great number of wrapping fingers which may be employed 25 it is possible to ornament with a great many colors or to use an extremely large number of separate threads in wrapping for the purpose of preventing runs or the like.

Now referring to Figs. 12-18, a modified form 30 of the invention will be shown which varies slightly from the first form in that movable fingers such as were employed throughout the needle carrier in the first instance are used in this modification in addition to other fingers which are permanently arranged in the carrier for clocking etc. A finger carrier 41 is fixed to rotate with a spindle 42 by means of a key 43. This spindle is reduced in size at 44 and is driven by means of a hollow shaft 45 having a slot for engagement 40 of a lug 46 projecting upwardly from a split collar 47. This collar is clamped to the reduced part of the spindle by means of a clamping screw 48 and imparts the rotation of shaft 45 to the spindle and thence to the carrier 41. This carrier is slotted in the same way the carrier 2 was and carries in some of these slots wrapping fingers 49 having butts 50. Yarns which are to be wrapped pass down through openings in the carrier as in the first instance and are threaded through openings 51 in the end of each finger. The carrier 41 has a cam assembly very similar to that of the first described form of the invention and which comprises a cap 52, sleeve 53 and a ring 54, the sleeve and ring being so shaped that they present a cam 55 within which butts 50 travel. These butts are forced downwardly to move their fingers to a lower level by the inclined part 56 of the cam groove, then along at a lower level 57 and again up within the inclined slot 58. While in 60 this lower position the fingers are tilted or rocked inwardly by cams presently to be described.

This rocking movement of the fingers is under the control of the cam 59 and the combined cams 60 and 61. The cams 60 and 61 are attached to 65 part of the sleeve 53 by means of suitable screws and are adjustable circumferentially of the cam assembly. These cams serve to hold the upper ends of fingers from rocking outwardly until such a time as they are to be positively moved by means of the cam 59. Two of these cams are employed in superposed relationship so that one may be adjusted with respect to the other thus to vary the length of the cam surface which acts upon the upper ends of these fingers. The cam 59 is also 75

adjustably secured in place on the ring 54 and serves to press against the lower ends of fingers and to rock them quickly within the needle circle as described above with respect to Figs. 1 and 9.

5 Once the finger is rocked inwardly of the needle circle it remains inside the needle circle due to the eccentricity and smaller size of the wrapping head with respect to the circle of needles wrapped. In this instance fingers are held inwardly, that is,

10 in the position shown in Fig. 13 throughout the extent of the cam 59 whereupon they will be straightened up and rocked outwardly by means of the inclined part on the inner side of the portion of the sleeve 53 which is indicated at 62,

15 Figs. 13 and 18. This beveled part of the sleeve allows rocking of the fingers but tilts them back into position as soon as they pass up on cam 59.

The ring 54 is attached to the sleeve by means of two connecting pieces 63 and 64. Both the ring 20 and the sleeve are slotted for the purpose of removing wrapping fingers, and a plate 65 having filler pieces 66 and 67 has been secured over these slots to render the said ring and sleeve continuous while functioning as a cam.

25 The sleeve 53 and the cap 52 form a groove within which flange 68 at the upper end of the carrier rotates. The carrier is also grooved at its lower end at 69 for the purpose of accommodating the cam 59.

30 Within some of the slots in this carrier special fingers 70 are to be inserted. These fingers being employed for the purpose of clocking or striping at parts of the stocking throughout a considerable length and wherein frequent change is not likely

35 to occur. Each of the fingers 70 is longer than the fingers 49 and carries a butt 71 at its upper end which engages with a cam slot at that end of the sleeve 53 for maintaining said fingers at a common elevation. This elevation will be that

40 shown in Fig. 15 or one in which the lower end of the fingers are not rocked or tilted within the carrier. For purposes of allowing the fingers to pass cam 59 without being affected thereby, each of the fingers is cut away as shown at 72. The 45 operation of this form of the invention will be apparent, the fingers 49 rocking in practically the same manner in which fingers 4 did, and the fingers 70 merely serving as yarn guides fixed with respect to the eccentrically mounted carrier, and 50 wrapping said group of selected needles in very much the same way one of the guides of Patent 1,702,608 would wrap selected needles.

Now referring to Figs. 19-23, we will describe a second modification of the invention wherein two 55 different types of swinging fingers are employed. The stationary clocking fingers may also be used in conjunction with the two types of movable fingers. A slotted carrier 73 similar to that of the previously described forms is fixed to the 60 end of a spindle 74 and a sleeve 75, cam ring 76 and cap 77 are arranged to be held stationary at the outside of the carrier so as to impart the reciprocating movements necessary to the yarn fingers. The carrier has a flange 78 which serves 65 the same purpose served by the flanges 22 and 68. For purposes of convenience the clocking fingers which would be similar to the fingers 70, Fig. 15, are not shown although it is contemplated to use as many of them as are necessary 70 or convenient with this form of wrapping mechanism.

Depending upon the pattern to be produced a number of long fingers 79 and short fingers 80 are spaced about the slotted carrier, the long 75 fingers having a butt 81 while the shorter fingers

have a butt 82 for the same purpose, but in addition thereto another butt 83 which cooperates with a special cam for swinging these fingers inwardly of the needle circle.

It is essential that this form of the invention be employed in conjunction with a double needle selection, that is, one wherein a first selection is made which allows needles to be wrapped at that position by one group of the wrapping fingers only, while a second selection provides for the

10 wrapping of other needles by the second group of wrapping fingers. Each of these selections allows wrapping by one type of finger to the exclusion of any effective wrapping by the other. One typical example of such a selection is shown in Fig. 23

15 wherein needles 84 having jacks 85 beneath them may be raised to one height as indicated by the pathway 86 when acted upon by any one of a series of selectors 87 functioning upon removable

20 selective butts, and thereafter being raised to the wrapping height by a cam 88 which engages a master butt on the jack in the event it has been selected. A second group of selectors 89 are arranged to select certain ones of the jacks which

25 were not selected by the first group or at the first stage of selection and thereby to cause them to engage a cam and be raised to a wrapping level which is higher than the first level as indicated by the pathway 90. This raising is accomplished

30 by contact of the master butts on these jacks with a cam 91. The fingers 80 will wrap needles which are raised to the lower wrapping level due to the fact that they are rocked inwardly of the needle circle sooner than the fingers 79. The fingers 79

35 will not be in a position to engage any of their wrap yarns within the hooks of needles raised to this lower wrapping level. The fingers 79 will thereafter be swung inwardly and will wrap their yarns about such needles as have been selected and elevated to the higher wrapping level. At 40 this time the fingers 80 have passed inwardly of the needle circle and have no tendency to interfere with the wrapping at this second stage.

Now considering the short wrapping fingers 80 which are maintained vertically within the carrier until they reach a point about at the beginning of the open space 92 in the sleeve 75, a cam

45 93 attached by suitable connecting means such as screws or the like in an adjustable manner to the cam ring 76 will swing these fingers 80 when they have passed down the cam slot between the sleeve and cam ring, the cam acting upon butts

50 83. The part 94 of the sleeve which is beneath the opening 92 has been beveled as illustrated in Figs. 19 and 20 so that these fingers may be swung as required. At the termination of the beveled portion the said fingers will be straightened up and will be raised by the oppositely inclined part of the cam slot which functions upon butts 82.

Two cams 95 and 96 attached to the sleeve 75 in a manner very similar to that described with respect to the cams 60 and 61 serve to hold the fingers 79 in vertical position while the fingers 80

are rocked inwardly for wrapping until such a time as they are to be swung inwardly by cam 97

65 similar to cam 59 of the modification previously described. Cam 97 will have no effect on the fingers 80 since they have already been moved to their inclined position and the cam 93 will likewise have no effect on the other fingers 79 since those fingers have no butts to be engaged by said cam. The clocking fingers such as 70 are to be used with this modification and will not be affected by cam 97 nor will they be contacted in any manner by the cam 93.

It will be evident that this modification of the invention allows wrapping at two separate wrapping points and thus presents all the advantages attendant upon such a method of wrapping, for example, it becomes possible to wrap adjacent needles with different yarns and to change from one wrapping yarn to another on adjacent needles and back to the first or to a similar yarn on the next adjacent needle all in the same course of knitting. These advantages are obtained with a very simple construction which at the same time provides for wrapping a maximum number of yarns or colors.

While it has not been described in this particular case, the eccentrically mounted wrapping head herein described may be constructed for relative shogging movements such as are commonly employed upon Banner wrap machines and as described in Patent 1,702,608. Other modifications and advantages will appear to those skilled in the art and will fall within the scope of the original invention herein disclosed. It is not intended to limit the same otherwise than by the express limitations of the claims themselves.

25 We claim:

1. In a circular knitting machine, means for feeding wrap yarns to needles of the machine in addition to a base yarn, including an eccentrically mounted, rotatable wrapping head, a plurality of 30 yarn guiding fingers therein and cams associated therewith constructed for moving said fingers in a vertical direction and thereafter for swinging said fingers for the purpose described.

2. In a knitting machine, means for feeding wrap yarns to needles of said machine including a rotatable carrier, a plurality of wrap yarn guiding fingers capable of sliding and of rocking within said carrier, cams operatively associated with said carrier and fingers constructed for moving said fingers downwardly after they have passed outside the needle circle and other cams functioning therewith for swinging fingers within the needle circle after they have been moved downwardly and for thereafter raising said fingers to their initial position.

3. In a circular knitting machine, the combination of a series of independently movable needles, means for selecting certain ones of said needles for being wrapped, means for wrapping pattern threads about said selected needles including a carrier rotatably mounted and eccentric with respect to the needles, fingers in said carrier arranged for sliding and for rocking therein, fixed cams associated with said carrier for imparting to said fingers a vertically sliding movement and other cams associated therewith for rocking said fingers.

4. In a circular knitting machine, the combination of a series of independently movable needles, means for selecting certain ones of said needles for being wrapped, means for wrapping pattern threads about said selected needles including a carrier rotatably mounted and eccentric with respect to the needles, fingers within said carrier arranged for sliding and for rocking, butts on said fingers and fixed cams associated with the carrier for engaging said butts and moving the fingers vertically downward and thereafter upwardly, another cam for rocking said fingers inwardly after they have been moved downwardly whereby said fingers will move across the path of needles more quickly than they otherwise would if dependent upon the eccentricity of the carrier alone.

75 5. In a circular knitting machine, the com-

bination of a series of independently movable needles, means for selecting certain ones of said needles for being wrapped, means for wrapping pattern threads about said selected needles including a carrier eccentrically mounted for rotation at the same angular speed as the needles, a plurality of yarn wrapping fingers in said carrier arranged for sliding therein and also for being rocked relatively thereto, certain ones of said fingers having butts thereon and said carrier having cams associated therewith for acting upon said butts and imparting vertical sliding movements to the fingers, a cam for imparting a rocking movement to said fingers, others of said fingers being fixed with respect to said carrier to be rotated therewith but being prevented from moving vertically therein or rocking with respect thereto.

6. In a circular knitting machine the combination of a series of independently movable needles, means for selecting certain ones of said needles for being wrapped with pattern threads, means for wrapping pattern threads about said selected needles including a carrier eccentrically and rotatably mounted with respect to said needles, a plurality of fingers arranged for sliding within said carrier and for rocking inwardly thereof, a plurality of cams circumscribing said carrier including cams for moving said fingers vertically, another cam for rocking said fingers 30 inwardly of the carrier and a third cam for controlling and preventing said rocking movement prior to the time when said fingers engage said cam for being rocked inwardly.

7. Mechanism as defined in claim 6, wherein 35 said cams for rocking fingers are adjustable circumferentially of the carrier.

8. Mechanism as defined in claim 6, wherein 40 said cams for preventing rocking of the fingers prior to a time when they engage the cam provided for that purpose are adjustable circumferentially of the carrier and also with respect to each other for the purpose described.

9. In a circular knitting machine, the combination of a series of independently movable 45 needles, means for selecting certain ones of said needles for being wrapped, means for wrapping pattern threads about said selected needles including a carrier eccentrically and rotatably mounted with respect to the needles, a plurality 50 of fingers for wrapping pattern threads about said selected needles arranged for sliding vertically and for rocking within said carrier, each finger having a butt thereon for engagement with cams for imparting vertical movements to 55 the fingers, cams for engaging said butts for imparting said movement, said ones of the fingers having another butt for engagement with a cam for imparting rocking movements to the fingers, a cam for engagement with said butts to impart 60 that rocking movement, and another cam for engaging those fingers which do not have said second mentioned butt to rock them inwardly of the carrier, the construction being such that either cam for imparting the rocking movement 65 will affect only the group of fingers for which it is intended.

10. In a circular knitting machine, the combination of a series of independently movable 70 needles, means for selecting certain ones of said needles for being wrapped, means for wrapping pattern threads about said selected needles including a carrier eccentrically mounted for rotation with respect to the needles, a plurality of 75 yarn wrapping fingers within said carrier ar-

ranged for sliding and rocking movement, said fingers having different conformations thereon and cams for causing said fingers to be moved for wrapping at different positions circumferentially of said machine.

11. In a circular knitting machine, the combination of a series of independently movable needles, means for selecting certain ones of said needles to be wrapped at one position about said machine and means for selecting others of said needles to be wrapped at a position more advanced in the direction of movement of needles about said machine, means for wrapping pattern threads about said selected needles including a carrier eccentrically and rotatably mounted with respect to the needles, a plurality of fingers for wrapping pattern threads arranged within said carrier for sliding movement and for rocking movement, said fingers being provided with differentiated butt formations and cams engageable with said butt formations to cause some of said fingers to be swung across the path of needles at the first point of needle selection and other cams for swinging the remaining fingers across the path of needles at said more advanced point of selection of needles.
12. In a circular knitting machine, the combination of a series of independently movable needles, means for selecting certain ones of said needles for being wrapped, some of said needles being selected at one stage and other being selected at a stage removed circumferentially of the machine from that first mentioned, means for wrapping pattern threads about said needles at both stages of selection including an eccentrically mounted carrier rotatable with respect to the said needles, a plurality of yarn wrapping fingers movable within said carrier for wrapping pattern

threads about selected needles, some of the fingers having differentiated butt formations thereon, cam means for moving said fingers downwardly at one point in the wrapping cycle and other cam means comprising two cams spaced circumferentially of the carrier, the first for imparting wrapping movements to some of the fingers at a point adjacent that where the needles are first selected and a second imparting like movements to the remaining fingers at the second point of needle selection.

13. A method of wrapping pattern threads about needles of a knitting machine including the steps of moving needles to a selected position for receiving a wrap thread, simultaneously moving a wrap thread carrier in a direction axially of the needle to meet said needle and to wrap a thread thereabout and thereafter moving said wrap thread carrier by a combined eccentric movement thereof with respect to the movements of a needle carrier and an independent movement of the wrap thread carrier, across a group of needles and then back to an inactive position.

14. A method of wrapping pattern threads about selected needles of a circular knitting machine including the simultaneous movement of needles and a wrap thread carrier in an axial direction of the needles and toward each other, then moving said wrap thread carrier across the path of the needles by a combined eccentric movement of a wrap thread carrier and an independent movement thereof so that by the cumulative effect of these movements, a wrap thread will be more rapidly passed in front of and behind the group of needles to be wrapped.
